UNITED STATES PATENT OFFICE.

WILLIAM H. GIBSON, OF LOS ANGELES, CALIFORNIA.

DESIGN FOR A SUPPORT FOR INKSTANDS AND THE LIKE.

Application filed February 23, 1928. Serial No. 25,544. Term of patent 3½ years.

To all whom it may concern:

Be it known that I, WILLIAM H. GIBSON, a citizen of the United States, residing at Los Angeles, county of Los Angeles, State of California, have invented a new, original, and ornamental Design for Supports for Inkstands and the Like, of which the following is a specification, reference being had to the accompanying drawing, forming a part thereof.

Fig. 1 is a perspective view of a support for inkstands and the like showing my new design,

Fig. 2 is a side view thereof, and

Fig. 3 is a front view thereof.

An ink stand is shown in dotted lines, resting upon the support.

I claim:

The ornamental design for a support for inkstands and the like as shown and described.

WILLIAM H. GIBSON.
